UNITED STATES PATENT OFFICE.

JOHN JANUCHOWSKY, OF ST. LOUIS, MISSOURI.

DESIGN FOR A BOTTLE-CAP REMOVER.

51,962.

Specification for Design.

Patented Apr. 9, 1918.

Application filed November 20, 1915. Serial No. 62,662. Term of patent 14 years.

To all whom it may concern:

Be it known that I, JOHN JANUCHOWSKY, a citizen of the United States, residing at St. Louis, in the State of Missouri, have invented a new, original, and ornamental Design for Bottle-Cap Removers, of which the following is a specification, reference being had to the accompanying drawing, forming part thereof, in which—

Figure 1 is a perspective view of the bottle-cap remover; and

Fig. 2 a top plan view thereof.

I claim:

The ornamental design for a bottle-cap remover, as shown.

JOHN JANUCHOWSKY.
